FISHING LURE

Emmett B. Owens, P.O. Box 971, Alamogordo, N. Mex.

Filed Mar. 9, 1960, Ser. No. 59,681

Term of patent 14 years

(Cl. D31—4)

I claim:

The ornamental design for a fishing lure, as shown.
